(57) **CLAIM**

The ornamental design for a handset front cover, as shown and described.

DESCRIPTION

FIG. 1 is a front perspective view of a handset front cover showing our new design;

FIG. 2 is a front view thereof;

FIG. 3 is a left side view thereof;

FIG. 4 is a right side view thereof;

FIG. 5 is a top view thereof; and,

FIG. 6 is a bottom view thereof.

The broken line showing the environmental structure of the handset front cover in FIGS. 1–6 is for illustrative purposes only and forms no part of the claimed design.
